UNITED STATES PATENT OFFICE.

AUGUSTIN REESE ERWIN, OF ENID, OKLAHOMA TERRITORY.

DESIGN FOR A HOLDER FOR CASTER-SPRINGS.

SPECIFICATION forming part of Design No. 33,920, dated January 15, 1901.

Application filed December 10, 1900. Serial No. 39,437. Term of patent 14 years.

To all whom it may concern:

Be it known that I, AUGUSTIN REESE ERWIN, a citizen of the United States, residing at Enid, in the county of Garfield and Territory of Oklahoma, have produced a new and original Design for a Holder for a Caster-Spring, of which the following is a specification.

This invention relates to a design for a holder for a caster-spring; and the leading feature consists in the design forming the subject-matter of the accompanying illustrations, wherein—

Figure 1 is a perspective view of a holder embodying the features of the design. Fig. 2 is a top plan view of the same.

The design is characterized by a scalloped rim 1, with inward radial projections at the

apices, as at 2, spaces 3 being formed between the bottom portions of the said projections and the upper plane of the rim. The alternate projections have extensions 4, and the scalloped rim produces a polygonal opening 5 with concave sides in appearance.

Having thus described the invention, what is claimed as new is—

The design for a holder for a caster-spring, herein shown and described.

In testimony that I claim the foregoing as my own I have hereto affixed my signature in the presence of two witnesses.

AUGUSTIN REESE ERWIN.

Witnesses:

VERNON W. WHITING,
JOHN WALTER ROBISON.
